UNITED STATES PATENT OFFICE.

LOUIS JANSON, OF BROOKLYN, ASSIGNOR, BY MESNE ASSIGNMENTS, TO
MATHILDA SALOMON, OF NEW YORK, N. Y.

GAGE ATTACHMENT FOR CANE-SHAVING MACHINES.

SPECIFICATION forming part of Letters Patent No. 378,591, dated February 28, 1883.

Application filed April 22, 1887. Serial No. 235,826. (No model.)

To all whom it may concern:

Be it known that I, LOUIS JANSON, of the city of Brooklyn, in the county of Kings and State of New York, have invented a certain new and useful Improvement in Gage Attachments for Cane-Shaving Machines, of which the following is a specification.

My invention has reference to the devices by which the knife-disks used on cane-shaving machines for gaging and trimming the cane-strips are adjusted circularly to present a new edge to the work and laterally to gage the width of the strips.

The object of my improvement is to provide a gage attachment for cane-shaving machines whereby greater convenience, accuracy, and security in the adjustment of the knife-disks are obtained than is ordinarily possible.

I will first describe in detail a gage attachment embodying my improvement, and then point out the various features of the said improvement in claims.

Reference is to be had to the accompanying drawings, forming a part of this specification, in which similar letters of reference indicate corresponding parts in all the figures.

Figure 1 is a side elevation illustrating the application to a cane-shaving machine of a gage attachment embodying my improvement.

Fig. 2 is a front elevation of the said attachment detached from the machine. Fig. 3 is a side elevation of the same, parts being removed to reveal the construction. Fig. 4 is a vertical sectional view on the line *ww*, Fig. 2. Fig. 5 is a reverse sectional plan view on the line *xx*, Fig. 2. Fig. 6 is a sectional plan view on the line *yy*, Fig. 2. Fig. 7 is a sectional plan view on the line *zz*, Fig. 2. Fig. 8 is a detail view of the spring for stiffening the adjustment.

A, Fig. 1, designates a cane-shaving machine of the usual description.

B designates the improved gage attachment, which is arranged in the ordinary way to bring the knife-disks C in the path of the cane-strip carried on the periphery of the revolving disk A'; and B' designates the bolts by which the frame B² of the attachment is secured to the main frame of the machine.

The face of the frame B² is beveled on opposite sides to a right angle, and in such beveled

sides are formed transverse dovetail guide-grooves B³, meeting at the angle, and in which are mounted to slide dovetail ribs D', formed on the inner faces of the carriers D. The carriers D, which are thus mounted to move in the horizontal plane toward and from each other, support the two knife-disks C, which are set and move at an angle of ninety degrees to each other, and have their inner edges beveled, so as to present parallel cutting-faces to the work.

The dovetail rib D' of each carrier D is formed lengthwise with an internally-threaded socket, D², and in it works the threaded thumb-screw E, which is formed on its outer part with an annular groove, E', engaged by a slotted plate, E², screwed to the corresponding rear beveled face of the frame B³, as shown clearly in Fig. 6. The thumb-screws E are thus held from lengthwise movement, while they are allowed to turn, so that by operating the same the carriers D, and with them the knife-disks C, may be adjusted toward and from each other for variously gaging the width of the cane-strips. A screw, D⁴, passed through a horizontal slot, D³, in each carrier and screwing in the frame B², is loosened when the carrier is to be adjusted, and tightened to clamp the carrier in place when so adjusted.

In a circular recess, F, formed in the front beveled face of an enlargement on the lower part of each carrier D, is mounted to turn a spur-wheel, G, having two studs, G', projecting from its face, which are secured in apertures in the corresponding knife-disk, C, so that the disk rotates with the spur-wheel. An outwardly-concave collar-spring, H, is held in the recess and bears against the back of the spur-wheel, and a screw-stud, I, having an enlarged head, is passed through apertures in the knife-disk, spur-wheel, and collar-spring H and screwed into the back of the recess. The headed screw-stud thus acts as a bearing for the spur-wheel and knife-disk, and, compressing them against the concave spring, prevents them from being turned or displaced by any jar or concussion.

Each spur-wheel is engaged and turned by the teeth of a rack-bar, K, the lower toothed end of which is guided in its vertical movement in a groove, K', formed in the front bevel-

eled face of the movable carrier D and in the downwardly - projecting extension D³ of the same.

The groove K' and the part of the rack in each extension D³ are covered by a plate, K², permanently secured to the same. A removable plate, K³, secured by a screw, K⁴, and a stud, K⁵, entering an aperture therein, and cut away at its front upper corner to accommodate the set-screw D⁴, covers the upper grooved portion of each carrier D and the rack therein.

The upper ends of both rack-bars K extend through vertical slots L' in and are connected to a vertically - movable block, L, by set-screws L², passed loosely through transverse slots L³ in the block and screwed into the rack-bars.

A hand-nut, M, is mounted to turn freely in the block L, but is held from longitudinal movement therein by a plate, M², screwed to the top of the block and engaging an annular shoulder, M³, on the nut.

The hand-nut M works on a vertical screw-bar, N, attached at its lower end to the top of the fixed frame B² of the attachment, so that by screwing the nut M up or down the block L is adjusted vertically and the rack-bars K move therewith to equally and simultaneously turn the spur-wheels G and attached knife-disks C, as desired.

A bar, P, fixed to and projecting downward from the block L, slides in a keeper, B⁴, on the rear upper part of the fixed frame B², and thus keeps the block L from turning and guides its vertical movement.

The slotted connection of the upper ends of the rack-bars K with the block L permits said bars to move bodily with the carriers D when the same are moved in adjusting the knife-disks laterally.

I claim as new and desire to secure by Letters Patent—

1. In a gage attachment for cane-shaving machines, the combination of a pair of knife-disks, gears for turning the same, a longitudinally-movable rack-bar engaging each of said gears, a movable block, to which both rack-

bars are connected, and means for adjusting said block to move both rack-bars simultaneously lengthwise, substantially as described. 50

2. In a gage attachment for cane-shaving machines, the combination of a knife-disk, a gear for turning the same, a rack-bar engaging the gear, a screw-bar, a nut working thereon, and a connecting device, through which the 55 rack-bar is moved lengthwise by the play of the nut on the screw-bar, substantially as described.

3. The combination of a frame for the gage attachment, knife-disks, gears and rack-bars 60 for turning the knife-disks, an adjustable block, to which the rack-bars are connected, and a slide-bar and keeper for guiding the movement of the block, substantially as described.

4. The combination of a frame for the gage 65 attachment, a carrier mounted to slide laterally thereon, a knife-disk and its actuating-gear on the carrier, a rack-bar engaging the gear, and an adjustable block for moving the rack-bar lengthwise, and attached thereto by 70 a pin-and-slot connection, substantially as described.

5. In a gage attachment for cane-shaving machines, the combination of a knife-disk carrier, a headed stud screwed therein, a knife-disk and its turning-gear mounted to turn freely on the said stud, and a stiffening-spring 75 interposed between the carrier and the gear of the knife-disk, substantially as described.

6. In a gage attachment for cane-shaving 80 machines, the combination of a frame having forward converging vertical sides, in which are formed transverse dovetail grooves, sliding knife-disk carriers having dovetail ribs adapted to said grooves and threaded sockets formed 85 lengthwise of and in the ribs, adjusting-screws working in the threaded sockets, and bearings fixed on the frame, in which the adjusting-screws are mounted to turn, substantially as described.

LOUIS JANSON.
